UNITED STATES PATENT OFFICE

FRED JACOBS, OF SPOKANE, WASHINGTON

TOWEL RACK

Application filed August 6, 1927. Serial No. 211,215.

My present invention relates to an improved towel rack which while adapted for use in various ways is particularly designed for attachment around the exterior of a hot water tank in order that the towels or other articles supported from the rack may be dried by being subjected to the heat radiated from the usual type of domestic hot water tank.

The towel rack comprises an attachment 10 including a sectional ring or band adapted to encircle and be secured about the exterior of the hot water tank, and a plurality of supporting arms are pivotally carried on the band. The invention consists in certain novel combinations and arrangements of parts involving the band and the rack arms or supports, as will hereinafter be more fully set forth and claimed.

In the accompanying drawings, I have 20 illustrated one complete example of the physical embodiment of my invention, and also illustrated a modified form of the invention, the parts being combined and arranged according to the best modes I have so far devised for the practical application of the principles of my invention.

Figure 1 is a view in elevation showing a domestic hot water tank with the towel rack of my invention attached thereto;

30 Fig. 2 is an enlarged view showing the towel rack detached;

Fig. 3 is a perspective view of the towel rack;

35 Fig. 4 is a view showing a portion of one end of the band with a modified support thereon;

Fig. 5 is a view showing the hooked end of the sectional band; and

40 Fig. 6 is a perspective view of a supporting clip which also performs the function of a filler for the band.

In order that the general arrangement and relation of parts may readily be understood, I 45 have shown in Fig. 1 a hot water tank T of

the usual domestic type having a base B and the usual pipes P.

The towel rack includes an annular band adapted to encircle the exterior of the tank, and this band comprises the sections 1 and 2 each of which are fashioned with flanges 3, and these flanges are secured together by bolts and nuts 4.

The free end 5 of the section 1 is provided with a series of vertically arranged slots 6, and the free end 7 of the section 2 is provided with a complementary hook 8 that is adapted to pass through a slot 6 from the exterior of the band, for the purpose of attaching the two free ends 5 and 7 rigidly together after the band has been applied to the hot water tank.

Each of the band sections is fashioned with exterior ribs 9 that form interior grooves 10. The metal of the band sections may be pressed or struck up by suitable machines to form these ribs and grooves, and the inner grooves 10 together with the exterior face of the hot water tank T form sockets in which the heads or ends 11 of the rack arms 12 are inserted. These rack arms as shown are of round bars with the head 11 bent at right angles to the arm 12, and the arm 12 may be swung on the head 11 as the pivot in order to gain access to different arms or racks of the device.

In Fig. 6, a perspective view of a clip 13 is shown, and in Fig. 2 this clip is illustrated in position to form a filler in the space between the tank and a free end of the annular band. This clip 13 has a pair of spaced inner plates 14 and the clip is fashioned with a vertical exterior rib 15 that forms an inner groove 16. The rack arm 17 has a bent head 18 as shown in Fig. 3 which fits down between the exterior face of the annular band and the inner face of the rib 15.

From this description, it will be apparent that I have provided a device of simple construction which may be manufactured at comparatively low cost, and which may be

assembled and applied with facility to the tank, and which will perform its functions as a towel rack in a proficient manner.

Having thus fully described my invention,
5 what I claim as new and desire to secure by
Letters Patent is—

The combination in a towel rack with a sectional band having spaced slots near one end and a complementary head at the other end,
10 of an adjustable space-filling clip of inverted U-shape in cross section having an exterior rib forming a groove, and a pivotal rack arm supported in said groove.

In testimony whereof I affix my signature.

15

FRED JACOBS.
